REINFORCED EXTENSIBLE INSULATOR

Clair S. Reed, Wayne, Mich., assignor to Van Dresser Specialty Corporation, Warren, Mich., a corporation of Michigan

Filed June 8, 1960, Ser. No. 34,720

10 Claims. (Cl. 5—354)

This invention relates generally to reinforced insulators for use in upholstered assemblies, and refers more particularly to a substantially flat horizontally extending elongated insulator for use between the padding and a supporting spring structure of an upholstered assembly.

One of the essential objects of the invention is to provide an insulator of the type mentioned wherein the insulator preferably includes a substantially rectangular extensible sheet of flexible material, and separate substantially parallel extensible reinforcing strands of substantially uniform length threaded loosely through said extensible rectangular sheet.

Another object is to provide an insulator wherein the flexible material of said rectangular sheet and said reinforcing strands have intermediate their end portions of undulating form, so that said rectangular sheet and said strands are extensible.

Another object is to provide an insulator wherein successive undulations respectively of said strands are disposed alternately upon opposite surfaces of said rectangular sheet and are disposed in vertically opposed relation to successive undulations of the flexible material of said rectangular sheet.

Another object is to provide an insulator wherein opposite end portions of said strands are upon one of the surfaces aforesaid of said rectangular sheet and terminate short of and adjacent to opposite ends of said rectangular sheet.

Another object is to provide an insulator wherein opposite end portions of the flexible material of the rectangular sheet are substantially flat and are terminally provided with open return bent or inwardly folded portions, and opposite end portions of the reinforcing strands have deformed portions preferably in the form of open return bent or substantially C-shaped portions.

Another object is to provide an insulator wherein the end portions and the deformed portions of the strands are disposed between the flat end portions and the return bent portions of the flexible material of the rectangular sheet, so that the deformed portions of the strands are covered by the open return bent portions of the flexible material of the rectangular sheet and are capable of being interlocked with the flexible material of the sheet to resist endwise movement of said strands bodily relative to said sheet.

Another object is to provide an insulator wherein the flat end portions of the flexible material of the rectangular sheet, the open return bent portions of said flexible material, the end portions of the reinforcing strands, and the open return bent portions of said strands at each end of the rectangular sheet have a common binder.

Another object is to provide an insulator wherein the binder at each end of the rectangular sheet is preferably formed of flexible sheet material and is held against displacement by means extending through the substantially flat end portions and the open return bent portions of the flexible material of the sheet at points between the end portions of the strands.

Another object is to provide an insulator wherein each binder is preferably formed from a material that is different than the flexible material of the rectangular sheet and comprises a separate strip extending transversely of the rectangular sheet.

Another object is to provide an insulator wherein the

2

flexible material of each binder is folded freely around the adjacent end of said rectangular sheet and has substantially flat substantially parallel portions respectively below the substantially flat portions and above the return bent portions of the rectangular sheet.

Another object is to provide an insulator wherein the means for holding each binder against displacement includes substantially aligned spaced means extending transversely of the rectangular sheet.

Another object is to provide an insulator wherein the rectangular sheet is preferably formed of burlap, the strands are preferably formed of wire, the binders at opposite ends of the rectangular sheet are each preferably formed of crepe paper, and the means for holding the binders against displacement are preferably formed of metal and are in the form of conventional type hog rings that may be conveniently stapled to the binders and to the flexible material of the rectangular sheet.

Another object is to provide an insulator that is simple in construction, economical to manufacture, and efficient in use.

Other objects, advantages and novel details of construction of this invention will be made more apparent as this description proceeds, especially when considered in connection with the accompanying drawing wherein:

FIGURE 1 is a perspective view of an upholstered assembly provided with a reinforced extensible insulator embodying my invention and showing parts broken away and in section.

FIGURE 2 is a fragmentary top plan view of an insulator embodying my invention.

FIGURE 3 is an enlarged fragmentary top plan view of the insulator, and showing parts broken away and in section.

FIGURE 4 is a longitudinal sectional view taken substantially on the line 4—4 of FIGURE 3.

FIGURE 5 is a fragmentary elevational view of one of the strands.

FIGURE 6 is a cross sectional view taken substantially on the line 6—6 of FIGURE 5.

In the drawing, A is a substantially rectangular extensible insulator embodying my invention disposed between a padding B for an exterior trim material C and a supporting spring structure D of an upholstered assembly.

As shown, the insulator A has a substantially rectangular extensible sheet 10 of flexible material, and separate substantially parallel extensible reinforcing strands 11 of uniform length threaded lengthwise through said extensible rectangular sheet.

The flexible material of said rectangular sheet 10 and said reinforcing strands 11 have intermediate their ends longitudinally extending portions 12 and 13 respectively of undulating form, so that said rectangular sheet and said strands are extensible. Successive undulations 14 respectively of said strands are disposed alternately upon opposite surfaces of the rectangular sheet 10 and are disposed in vertically opposed relation to successive undulations 15 of the flexible material of the rectangular sheet 10. Opposite end portions 16 of said strands 11 are upon the upper surface of the rectangular sheet 10 and terminate short of and adjacent to opposite ends of the rectangular sheet.

Preferably opposite end portions 17 of the flexible material of the rectangular sheet 10 are substantially flat and are terminally provided with open return bent or inwardly folded portions 18, and opposite end portions 16 of the reinforcing strands have deformed portions, preferably in the form of open return bent or substantially C-shaped portions 19. The end portions 16 and the deformed portions 19 of the strands 11 are disposed between

the flat end portions 17 and the return bent portions 18 of the flexible material of the rectangular sheet, so that the deformed portions 19 of the strands are covered by the open return bent portions 18 of the flexible material of the rectangular sheet and are capable of being interlocked with the flexible material of the rectangular sheet to resist endwise movement of the strands bodily relative to said rectangular sheet.

In the present instance, the flat end portions 17 of the flexible material of the rectangular sheet, the open return bent portions 18 of said flexible material, the end portions 16 of the reinforcing strands 11, and the deformed portions 19 of said strands at each end of the rectangular sheet 10 have a common binder 20. Preferably each binder 20 is folded freely around the ends of the rectangular sheet 10 and has substantially flat substantially parallel portions 21 and 22 respectively located below the substantially flat portions 17 and above the return bent portions 18 of the rectangular sheet 10.

Each binder 20 is formed of flexible sheet material, and the substantially flat substantially parallel portions 21 and 22 thereof are held against displacement by fasteners 23 extending through the substantially flat end portions 17 and the open return bent portions 18 of the flexible material of the rectangular sheet at points between the end portions 16 of the strands. Preferably each binder 20 is formed from a material that is different than the flexible material of the rectangular sheet 10 and comprises a separate strip extending transversely of the rectangular sheet.

The fasteners 23 at each end of the rectangular sheet 10 are spaced apart and are substantially in alignment. Such aligned spaced fasteners 23 extend transversely of the rectangular sheet 10 at points substantially midway between the respective folds 24 of the binders 20 and the free edges 25 and 26 respectively of the substantially flat substantially parallel portions 21 and 22 respectively of the binders 20.

Although the various elements of my insulator may be formed of any suitable material for the purposes set forth, the rectangular sheet 10 is preferably formed of burlap, the strands 11 are preferably formed of wire, the binders 20 at opposite ends of the rectangular sheet 10 are preferably formed of crepe paper, and the fasteners 23 are preferably formed of metal and comprise conventional type hog rings that may be conveniently stapled to the binders 20 and to the flexible material of the rectangular sheet 10.

Thus, from the foregoing, it will be apparent that the insulator A is used between the padding B and the supporting spring structure D of an upholstered assembly, such for example a seat or seat back of a motor vehicle, and that in use the opposed undulations 14 and 15 respectively of the strands 11 and of the rectangular sheet 10 will flex toward one another and thereby will permit both of said elements, namely the rectangular sheet 10 and the strands 11, to be longitudinally extensible to compensate for localized loads imposed upon them by one or more seated persons. Such binders 20 not only facilitate the handling and removal of the insulators A when arranged in a stack, but also serve effectively to protect the padding B of the upholstered assembly from the deformed end portions 19 of the strands, and thereby preclude objectionable abrasion or tearing of such padding B when the insulators are installed.

What I claim as my invention is:

1. An elongated composite insulator for use between an overlying padding and an underlying supporting spring structure of an upholstered assembly; comprising an elongated substantially horizontally extending sheet of flexible material, and substantially horizontally extending substantially parallel separate reinforcing strands threaded loosely lengthwise through said sheet, the flexible material of said sheet and said reinforcing strands having in each instance intermediate their ends portions of un-

dulating form so that both said sheet and said strands are extensible when subjected to a localized load.

2. The structure defined in claim 1, wherein successive undulations respectively of said strands are disposed alternately upon opposite surfaces of said sheet and are disposed in vertically opposed relation to successive undulations of said sheet.

3. The structure defined in claim 1, wherein opposite end portions of said sheet are terminally provided with open return bent portions, and opposite ends of said strands have deformed portions between and covered by the opposite end portions and the return bent portions of said sheet, the deformed portions of said strands being capable of being interlocked with one of the portions aforesaid of said sheet to resist endwise movement of said strands bodily relative to said sheet.

4. The structure defined in claim 3, wherein the end portions and the return bent portions of said sheet and the deformed portions of said strands at each end of said sheet have a common binder.

5. The structure defined in claim 4, wherein each binder is formed of flexible material and is held against displacement by means extending through the end portions and the return bent portions of said sheet.

6. The structure defined in claim 5, wherein each binder comprises flexible material folded freely around an adjacent end of said sheet, and wherein the folded material has substantially flat substantially parallel portions respectively below an adjacent end portion of said sheet and above an adjacent return bent portion of said sheet.

7. The structure defined in claim 6, wherein the sheet is formed of burlap, the strands are formed of wire, the binders are each formed of crepe paper, and the means for holding the binders against displacement are formed of metal.

8. An elongated composite insulator for use between an overlying padding and an underlying supporting spring structure of an upholstered assembly; comprising an elongated horizontally extending sheet of burlap provided at opposite ends thereof with substantially flat portions and provided intermediate said flat portions with vertically extending alternately arranged upwardly and downwardly opening curved portions, and horizontally extending substantially parallel reinforcing wires threaded loosely lengthwise through said sheet, said wires having portions upon the flat portions aforesaid of said sheet and being provided intermediate the portions just mentioned with vertically extending alternately arranged upwardly and downwardly opening curved portions, the upwardly opening curved portions of said sheet being vertically opposed to, spaced from, and capable of being flexed toward downwardly opening curved portions of said wires when subjected to a localized load, and downwardly opening curved portions of said sheet being vertically opposed to, spaced from, and capable of being flexed toward upwardly opening curved portions of said wires when subjected to a localized load.

9. An elongated composite insulator for use between an overlying padding and an underlying supporting spring structure of an upholstered assembly; comprising an elongated horizontally extending sheet of fabric provided intermediate opposite ends thereof with vertically extending upwardly opening curved portions and vertically extending downwardly opening curved portions, and horizontally extending substantially parallel reinforcing strands threaded loosely lengthwise through said sheet intermediate the upwardly and downwardly curved portions thereof, said strands being provided intermediate opposite ends of said sheet with curved portions, the upwardly opening curved portions of said sheet being vertically opposed to, spaced from, and capable of vertical movement toward curved portions of said strands when subjected to a localized load, and the downwardly opening curved portions of said sheet being vertically opposed to, spaced from, and capable of vertical movement toward

70

75

curved portions of said strands when subjected to a localized load.

10. An elongated composite insulator for use between an overlying padding and an underlying supporting spring structure of an upholstered assembly; comprising an elongated horizontally extending sheet of flexible material, and horizontally extending substantially parallel reinforcing strands threaded loosely through said sheet, the flexible material of said sheet and said reinforcing strands having in each instance vertically extending curved por- 10

tions capable of relative vertical movement toward each other when subjected to a localized load.
